FLYCATCHER

Frank Travnicek, East St. Louis, Ill., now by
change of name Frank Griness

Application February 23, 1940, Serial No. 320,339

2 Claims. (Cl. 43—116)

This invention relates to a fly catcher having a web of paper coated with a sticky viscous substance or lure.

An object of the invention is to provide a fly paper intended to be suspended in a vertical position or plane, with a coating of viscous lure which will have means for retarding the flow of the lure downwardly. In warm temperatures any coating of this character has a tendency to run and when such a paper is suspended in a vertical position it may run to such an extent as to leave at least a portion of the surface improperly coated.

Another object of the invention is to provide a device for supporting a roll of paper attached to a crank in such a manner that the paper may be wound upon the crank to expose fresh coated surfaces of the paper.

Other objects are to provide a device of the character described, which will be economical in construction and convenient to use, and to provide additional advantages which will be apparent from the following description, taken in connection with the accompanying drawing.

Fig. 1 is a side elevation partly in section, showing a device embodying this invention;

Fig. 2 is a vertical section on line 2—2, Fig. 1;

Fig. 3 is an end elevation of another embodiment of the invention;

Fig. 4 is a vertical section on line 4—4, Fig. 3; and

Fig. 5 is a section of the paper on line 5—5, Fig. 1.

The device includes a frame which supports a roll of paper with a web in a vertical position, the roll in one embodiment (Figs. 1 and 2) being situated in a casing containing a viscous lure which coats the web. A crank in the upper part of the frame is connected to the web so as to expose a fresh portion of the web. In another embodiment (Figs. 3 and 4) the spool is supported on the frame while the web is guided through the container. The paper is embossed, or perforated, so as to better hold the viscous coating. The construction and operation of the device will be apparent from the following detail description.

The frame includes a base 1 attached to and supporting a pair of uprights 2, spaced from each other and connected at their top ends by a cross bar 3, which serves as a handle for the device. Below the cross bar 3, a crank shaft 4 is journaled in the upper portion of the uprights 2.

The receptacle 5 is positioned adjacent or on

the base 1, and is held in position by a cross bar or pin 6 which passes through holes in the uprights 2, and in notches 7 in end walls 8 of the receptacle. The receptacle is provided with a removable lid 9, so formed as to provide a slot 10 at the top of the receptacle. A spool 11, carrying a roll of paper 12, is positioned in the receptacle below the rod 6, the rod 6 serving to hold the spool against displacement. A web of the paper extends from the spool through the slot 10 upwardly in a vertical position to a line of attachment with the crank 4. The receptacle 5 is adapted to hold a quantity of viscous tacky lure 13. This lure is such that it will attract flies to it and will hold them when they light upon it.

The lure being generally stiff and tacky will adhere to the paper, but because the effective web of the paper is in a vertical position there will be a tendency for the fluid to flow downwardly, especially in hot temperatures. To improve the paper in this respect it is preferably embossed, as best shown in Fig. 5. As shown these embossments comprise a series of corrugations 14. It will be understood, of course, that these embossments need not be in a line or need not be continuous. While the embossments are preferred, perforations may also be used to the same effect.

In the embodiment shown in Figs. 3 and 4, the spool 11 is supported on a shaft 15 outside the receptacle 5. In this case the web 12 passes from the spool 11 downwardly through the slot 10 in the top of the container adjacent the rod 6, then under and around a bar 16 in the container, through the tacky material 13 and upwardly through the slot 10 to the crank 4.

Some of the results of this invention may be accomplished by pre-coating the roll of paper with a tacky lure, so that it is unnecessary to run the web of paper through a mass of the lure.

It will be understood that the rod 6 may be readily removed, in which case the container 5 as well as the spool 11 (in the embodiment Figs. 1 and 2) may be quickly removed and replenished or replaced.

From the foregoing description it will be seen that the invention accomplishes its objects. A fly paper has been provided with means for suspending it in a vertical plane and having means for retarding the flow of the lure downwardly. A device has been provided by which the web of a roll of paper may be attached to a crank in such a manner that the web will be suspended in a vertical position and, by the crank, a web

with freshly coated surface or surfaces will be exposed.

Various changes may be made in the details of construction, within the scope of the appended claims, without departing from the spirit of this invention, and parts of the invention may be used without the whole.

I claim:

1. A fly catcher comprising a base, a pair of uprights secured to the base, a crank shaft journaled on the upper portion of the uprights, a receptacle adapted to contain a fluid seated upon the base, a spool in the receptacle, a web of paper on the spool having an end connected to the crank, and a removable bar passing through

15

the uprights in a position to engage the top of the receptacle and the spool.

2. A fly catcher comprising a base, a pair of uprights secured to the base, a cross bar connecting the upper ends of the uprights, a crank shaft journaled in upper portions of the uprights below said cross bar, a receptacle adapted to contain a fluid seated upon the base vertically below said crank shaft, a web of paper having an end connected to the crank and extending downwardly into the receptacle, and a removable bar passing through the uprights and through notches in end walls of the receptacle.

FRANK TRAVNICEK.
